UNITED STATES PATENT OFFICE

168,646

SPOOL HOLDER

Celeste M. Erickson, Chicago, Ill.

Application September 5, 1952, Serial No. 21,351

Term of patent 14 years

(Cl. D3—19)

To all whom it may concern:

Be it known that I, Celeste M. Erickson, a citizen of the United States, residing at Chicago, county of Cook, and State of Illinois, have invented a new, original, and ornamental Design for a Spool Holder, of which the following is a specification, reference being had to the accompanying drawing, forming a part thereof, in which:

I claim:

The ornamental design for a spool holder, substantially as shown and described.
